Primary Examiner — Vy N Koenig*Assistant Examiner* — Elizabeth Anne Glassberg(74) *Attorney, Agent, or Firm* — Saxton & Stump, LLC(57) **CLAIM**

The ornamental design for a chicken coop, as shown and described.

DESCRIPTION

FIG. 1 is a top-front-left side perspective view of a chicken coop showing our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the figures illustrate portions of the chicken coop that form no part of the claimed design.

1 Claim, 4 Drawing Sheets(56)
